UNITED STATES PATENT OFFICE.

DIRK LELY, JR., OF EINDHOVEN, NETHERLANDS, ASSIGNOR TO GENERAL ELECTRIC COMPANY, OF NEW YORK, N. Y.

HEADLIGHT FOR ROAD VEHICLES OR THE LIKE.

Application filed May 11, 1921. Serial No. 468,736.

To all whom it may concern:

Be it known that I, DIRK LELY, Jr., a subject of the Queen of the Netherlands, residing at Eindhoven, in the Province of 5 North Brabant, in the Kingdom of the Netherlands, have invented certain new and useful Improvements in Headlights for Road Vehicles or the like (for which I have filed an application in the Netherlands on May 1, 10 1920, Serial No. 14,690 Ned.), of which the following is a specification.

My invention relates to headlights designed to project upon the road in advance of a traveling vehicle, a non-glaring clear 15 beam of light of wide lateral or horizontal spread and of limited vertical spread, and in addition thereto a diffused field of light in all forward directions. This object is secured by the arrangement of a 20 peculiar source of light in a peculiar reflector, as will appear from the following detail description with reference to the accompanying drawing, in which:

Fig. 1 is an end view of my improved 25 lighting unit, looking toward the opening of the reflector.

Fig. 2 is a vertical axial section on line 2—2 of Fig. 1.

Fig. 3 is a horizontal axial section on line 30 3—3 of Fig. 1 and Fig. 4 is a view of the projection of a clear beam upon a vertical plane.

The reflector used in my system is preferably a paraboloid 10, so that the axial sections shown in Figs. 1 and 2 are parabolas. At the vertex of this paraboloid is an opening for the reception of the socket 11 of an incandescent lamp 12, which is removably and exchangeably held in the socket. The 40 incandescent filament of the lamp is a single closely wound spiral 13, which is in effect a long rectilinear source of light of small cross section. When the lamp is in its proper position, the axis of the filament is horizontal, at right angles to the axis of the reflector, as indicated in Figs. 1 and 3, and with its middle portion in the focus of the latter.

The inner surface of the paraboloid reflector, which is clearly shown, particularly in Fig. 1, has only two specular bands of moderate width which are highly reflecting, one of these bands, 14, extending meridionally from the front edge of the 55 paraboloid to and beyond the vertex and

returning to the diametrically opposite part of the edge, in a horizontal direction, and the other band 15, extending in like manner in a vertical direction. The sectoral portions 16, of the inner face of the reflector between the bands 14, 15, are etched or sand-blasted or otherwise frosted or made dull, to act as diffusers of the light incident thereon. These diffusing sectors are conspicuously marked in the drawing by appropriate dark, granular shading.

The effect of the construction described is as follows: The horizontal, specular, meridional band 14 projects into the field of illumination an enlarged horizontal image 70 of the axial extent of the rectilinear filament 13, while the vertical, specular, meridional band 15, projects in like manner an enlarged vertical image of the diameter of the rectilinear filament. Upon a vertical 75 plane placed at any distance from the headlight at right angles to the axis of the reflector, the intercepted image has the form indicated in Fig. 4, which shows the wide lateral spread 13' 13' of the beam due to the 80 length of the filament and the horizontal, specular band 14, and the limited, narrow, vertical spread 13² of the beam due to the diameter of the filament and the vertical specular band 15.

Normally the headlight is mounted with the axis of the paraboloidal reflector in a horizontal position, that is to say, parallel or slightly inclined to the even roadbed, and consequently the latter will be conspicuously 85 lighted in front of the vehicle throughout a wide space to the right and left of the running direction of the vehicle and the illumination will rise vertically to a very limited extent, so that a pedestrian in front 90 of the vehicle or a driver of a vehicle running toward the headlight will experience no glare.

In addition to this, the granular etched or sand-blasted sectors 16 produce a mild, 100 widely diffused illumination as a background to the defined beam, whereby the contrast between this beam and its background is largely reduced, so that an accidental rise of the defined beam which may strike the eye 105 of a pedestrian will have less glaring effect than if the background to the defined beam were quite dark.

In addition to the production of a diffused light field by the frosted sectoral parts of 110

the reflector, this frosting has also another and very important function. If the frosting were omitted, so that the whole inner surface of the reflector were specular, the 5 sectoral portions would project into the field of illumination a variety of images of the spiral filament, variously inclined, all of which would merge into each other and produce an ill defined field of illumination. 10 By restricting the specular surface of the reflector to the two bands 14, 15, a single, well defined image of the light source is projected, and the frosted sectoral surfaces are utilized for the production of a diffused 15 background as hereinbefore described.

While the diffused field surrounding the defined beam is preferably produced by frosting the surfaces of the sectors between the specular bands, as herein described, other 20 means having a like effect may be used as, for instance, the bulb of the incandescent lamp may be frosted in such parts which would otherwise allow the issue of undesirable defined beams.

25 Having now fully described my invention,

I claim and desire to secure by Letters Patent:

1. A headlight comprising a paraboloidal reflector having two meridional, specular band surfaces at right angles to each other 30 and the sectoral spaces between the bands frosted, with a rectilinear source of light with its axis intersecting the axis of the paraboloid at the focus and extending within one of the bands across the width of same. 35

2. A headlight comprising a paraboloidal reflector having a horizontal and a vertical meridional, specular band surface and the intervening sectoral spaces frosted, with a single rectilinear spiral filament disposed 40 with its axis horizontal across the focus and within the width of the horizontal band.

In witness whereof, I have hereunto signed my name in the presence of two subscribing witnesses.

DIRK LELY, JR.
